UNITED STATES PATENT OFFICE.

EDMUND B. KIRBY, OF ROSSLAND, CANADA.

PROCESS FOR DISTILLING OFF THE OIL FROM OIL-COATED FINES.

No. 825,909.

Specification of Letters Patent.

Patented July 17, 1906.

Application filed December 14, 1903. Serial No. 185,031.

To all whom it may concern:

Be it known that I, EDMUND B. KIRBY, a citizen of the United States, residing at Rossland, in the Province of British Columbia and Dominion of Canada, have invented a certain new and useful Improvement in Processes for Distilling Off the Oil from Oil-Coated Fines, of which the following is a full, clear, and exact description, reference being had to the accompanying drawings.

In practicing any of the so-called "oil processes" of concentrating ores it is impossible to remove by mechanical means alone all of the oil which has adhered to the mineral particles. The separation and recovery of such oil from the concentrates by distillation is one step in an oil process which I have invented.

My invention resides in the method of distilling off the oil in a manner which shall require the least attention on the part of the operator and which shall include as a characteristic the automatic feeding of the material through the heat zone. The material under treatment is the product of the so-called "oil-concentrating" process, wherein the mineral fines are agitated with oil and water, with the result that some of the mineral particles, usually the metal and metallic minerals, become by reason of adhesive preference coated with the oil, while the other particles are not so coated, but remain suspended in the water. The oil-coated particles float to the surface of the water, forming a thick layer of oil and oil-coated mineral particles. The other mineral particles tend to settle out of the water to the bottom of the tank in which this mixture is contained. The particles selected out by the oil are skimmed off and as much as possible of the oil associated therewith is separated by mechanical means. To separate the oil not conveniently removed by mechanical means is the object of my process.

Referring to the parts by letters, A represents a retort-furnace of any suitable form adapted to supply the necessary heat to the retort. B represents an inclined retort which is suitably set in said furnace. This retort has at its upper end a substantially vertical charging-neck C and at its lower end a substantially vertical discharging-spout D. The retort B is set at approximately the

"angle of repose" of the oil-wet concentrates which are to be charged into the same, wherefore as the oil is vaporized said concentrates will slide by gravity downward. They will not, however, entirely fill the retort, wherefore the upper part thereof will remain sufficiently open for the upward passage of the vapors.

The retort is maintained at the distillation temperature of the oil used, which in the case of kerosene is about 338° Fahrenheit. In order to assist in carrying off the oil-vapor, a current of superheated steam is introduced into the retort through a pipe b, and said steam and oil vapors pass off through pipe F to the condensing apparatus. The dry concentrates on losing their oil and moisture slide down toward the lower end of the retort into the discharge-neck, from which they are withdrawn through the double gates E E in said spout, which gates are to be opened alternately, so as to prevent the escape of vapors. The spout above one gate or the other will always be full of the dry concentrate, which itself acts as a seal. The upper end of the neck C is made hopper-shaped, and the fresh charge of the wet concentrate is admitted from the charging-neck and hopper past the double sliding gates G G, which are opened alternately. The mass of the concentrates in the hopper and in the spout above one or both of said gates acts as an efficient seal. It is not necessary that the gates E E or G G shall be tightly fitting, since it is not intended that they shall seal the retort, this being done by the concentrates resting upon them. In other retorts various kinds of covers are necessarily employed to seal the retort, because such retorts have been designed for use and have been used with material which cannot act as a seal when supported upon loose-fitting gates.

The vapors which pass off through pipe F are led through a settling-chamber K, which catches any dust of the concentrates which may pass off with the vapors, and then the vapors pass to a condenser M of any approved construction.

Having described my invention, I claim—

The process of treating oil-concentrated mineral fines which consists in feeding the same into a retort maintained at the temperature necessary for distillation of the oil

present, and automatically regulating the feed of the concentrates through the heat zone by so disposing the charge, that said concentrates will when wet remain within the 5 heat zone by their adherence to the supporting medium, but that when dry the decreased frictional resistance will not be sufficient to retain them within said zone, collecting the

dry concentrates and leading away the distilled vapor.

In testimony whereof I hereunto affix my signature in the presence of two witnesses.

EDMUND B. KIRBY.
